WELLHOLE CLEANING DEVICE

Clark E. Braden, Salem, W. Va.

Application May 27, 1939, Serial No. 276,120

5 Claims. (Cl. 166—18)

This invention relates to a wellhole cleaning device and has for its object to provide a tool for insertion in wellholes having an expansible brush adapted to be expanded into engagement with the walls of the hole when the tool contacts with the bottom of the hole whereby the walls are cleaned upon reciprocation of the tool.

A further object of the invention resides in adjustably mounting the tufts of bristles in the brush head to permit extension of the bristles as they become worn down and renewal of the bristles when necessary.

Another object of the invention resides in providing a device of the above-mentioned character which is simple and durable in construction, reliable and efficient in operation, and inexpensive to manufacture.

Other objects and advantages of the invention will be apparent during the course of the following description.

In the accompanying drawings forming a part of this specification and in which like numerals are employed to designate like parts throughout the same,

Fig. 1 is a side elevation of the device,

Fig. 2 is a longitudinal sectional view of the device,

Fig. 3 is an enlarged section through one of the socket members for holding the bristles,

Fig. 4 is a detail view of the cylinder part of the socket member,

Fig. 5 is a detail view of the nut applied to the cylinder as shown in Fig. 4,

Fig. 6 is an end view of the socket member assembled with a tuft of bristles therein, and

Fig. 7 is a side elevation of the tuft of bristles.

In the drawings, wherein for the purpose of illustration I have shown a preferred embodiment of my invention, the numeral 5 denotes a barrel threaded at one end to a solid head 6 having the usual threaded pin 7 adapted to fit a standard jar. The bore of the barrel at its other end is reduced in diameter, as at 8, forming a shoulder 9 inside of the barrel, and

openings 10 are provided in opposite sides of the barrel adjacent the shoulder for receiving the heads 11 of the spring dogs 12 seated in recesses in the outer wall of the barrel, the dogs being secured at one end by screws 13 which permit

the heads 11 to move laterally in and out of the openings. A plunger 14 is slidably mounted in the reduced bore of the barrel having a circular head 15 formed integral with its inner end, the periphery of the head being beveled, as at 16,

for engagement in the notches 17 formed in the

heads 11 of the spring dogs, when the plunger is moved inwardly. The head 15 is adapted to contact the shoulder 9 to limit the outward movement of the plunger and inward movement of the plunger is limited by a stop bolt 18 disposed centrally in the barrel and adjustably secured in the head 6 by a lock nut 19. By adjusting the bolt 18 the extent of movement of the plunger may be controlled. A screw 20 in the side of the barrel intersects the reduced bore and engages in a longitudinal groove 21 in the side of the plunger to secure the plunger against rotation. An expansible sleeve or brush head 22 is slidably mounted on the free end of the plunger and is secured thereon by means of a cap 23 threaded on the end of the plunger, the cap being locked in position by a set screw 24. The brush head 22 is preferably constructed of rubber or other suitable material, each end having an inturned flange 25 to form a bearing for the plunger. The cap 23 is provided with a central recess 26 which is threaded to receive an extension rod, not shown, to limit the downward movement of the device in the well. The barrel 5 is locked to the head 6 by a set screw 27. The ends of the recesses in which the spring dogs 12 are seated have notches 35 at one end to permit a tool to be inserted for raising the spring dogs to release the heads 11 from engagement with the head of the plunger 14, to permit the brush head to be collapsed when inserting the tool in the wellhole.

The tufts of bristles 28 are secured to the brush head 22 by socket members 29 which are more clearly disclosed in Figs. 3 to 6, inclusive. The members 29 include a cylinder 30 adapted to pass through the wall of the brush head and at one end is provided with a head 31 having prongs 32 which are driven into the inner wall of the head to firmly secure the cylinder in place. The other end of the cylinder is exteriorly screw-threaded to receive the hexagonal nut 33 which is provided with a tapered bore. The cylinder is slotted longitudinally at its outer end, as at 34, forming compressible fingers which are bent inwardly when the nut 33 is threaded on the end of the cylinder. The tufts of bristles 28 are bent intermediate their ends, as shown in Fig. 7, and then inserted through the cylinder with the free ends of the bristles extending beyond the outer wall of the brush head. When the nut 33 is screwed down on the cylinder the compressible fingers are pressed inwardly into clamping engagement with the tuft of bristles, securely holding the same in its set position. As the

ends of the bristles wear away, the tufts of bristles may be adjusted in the socket members to extend the ends of the bristles. If desired, the socket members may be molded in the wall of the brush head during the course of manufacture.

In use, the device is lowered into the wellhole and upon contacting the bottom of the well, the plunger 14 is moved inwardly of the barrel 5, thereby expanding the brush head 22 into engagement with the wall of the wellhole. As the plunger moves inwardly, the head 16 spreads the spring dogs apart until the head 15 engages in the notches 17, thus securing the plunger in its compressed position. If further expansion of the brush head is desired, the bolt 18 may be adjusted to permit further movement of the plunger until the head 15 is past the heads of the spring dogs which engage beneath the head 20 of the plunger and hold it in its set position. After the brush head is expanded the tool is reciprocated up and down in the wellhole, thus causing the bristles to thoroughly clean the wall of the hole.

It is to be understood that the form of my invention herein shown and described is to be taken as a preferred example of the same and that certain changes in the shape, size, and arrangement of the parts may be made without departing from the spirit of the invention or scope of the subjoined claims.

Having thus described my invention, I claim:

1. A wellhole cleaning device comprising a barrel, a plunger mounted to reciprocate in one end of said barrel, an expandable brush head mounted on the outer end of said plunger, a cap securing said head on said plunger adapted to expand said head upon inward movement of said plunger, and spring dogs mounted in said barrel adapted to engage and hold said plunger when moved inwardly.

2. A wellhole cleaning device comprising a barrel, a plunger mounted to reciprocate in one end of said barrel, a cap secured on the outer end

of said plunger, an expandable tubular brush head mounted on said plunger between said cap and barrel, means for holding said plunger when pressed inwardly to expand said brush head, and tufts of bristles mounted in said brush head.

3. A wellhole cleaning device comprising a barrel, a plunger mounted to reciprocate in one end of said barrel, a cap secured on the outer end of said plunger, an expandable tubular brush head mounted on said plunger between said cap and barrel, spring dogs mounted in the side of said barrel, a head formed integral with the inner end of said plunger adapted to be engaged by said dogs when the plunger is moved inwardly to expand said brush head, said dogs having means for securing said head against movement in one direction, and tufts of bristles mounted in the wall of said brush head.

4. A wellhole cleaning device comprising a barrel, a plunger mounted to reciprocate in one end of said barrel having a head at its inner end, a cap secured on the outer end of said plunger, an expandable tubular brush head mounted on said plunger between said cap and barrel, spring dogs mounted in the side of said barrel adapted to engage and hold the head of said plunger when the plunger is moved inwardly to expand said brush head, means for limiting the inward movement of said plunger, and tufts of bristles mounted in the wall of said brush head.

5. A wellhole cleaning device comprising a barrel, a plunger mounted to reciprocate in one end of said barrel having a head on its inner end, a cap secured on the outer end of said plunger, an expandable tubular brush head mounted on said plunger between said cap and barrel, spring dogs mounted in the sides of said barrel adapted to engage the head of said plunger when the plunger is moved inwardly to expand said brush head, socket members mounted in the wall of said brush head, and tufts of bristles adjustably secured in said socket members.

CLARK E. BRADEN.
